HAULING MACHINE

Abel Léo Charles Blondelle, Paris, France, assignor to Enterprises Métropolitaines Et Coloniales, Paris, Seine, France, a society of the Republic of France

Application June 17, 1946, Serial No. 677,173
In France October 19, 1945

7 Claims. (Cl. 104—183)

1

The present invention relates to hauling machines for railroad plants intended to permit the displacement of railway cars and other movable engines, and it is more especially, although not exclusively, concerned, among these machines, with hauling winches.

The object of my invention is to provide a machine of this kind which is easily movable along tracks so as to permit of bringing it into the position where its working is most efficient, such a displaceable hauling machine being capable of replacing a relatively great number of fixed machines as were used up to the present time.

Other objects of my invention will result from the following detailed description of some specific embodiments thereof with reference to the accompanying drawings, given merely by way of example, and in which:

Fig. 1 is a plan view of a hauling winch made according to a first embodiment of my invention;

Fig. 2 is a plan view on an enlarged scale of the rolling system of this machine;

Figs. 3 and 4 are sectional views, respectively on a line at right angles to the track and on a line parallel thereto, of some element of this machine;

Figs. 5 and 6 are an elevational view and a plan view, respectively, of a hauling winch made according to another embodiment of my invention;

Fig. 7 is a vertical cross sectional view of the machine of Figs. 5 and 6;

Fig. 8 is a corresponding horizontal cross sectional view;

Fig. 9 is a corresponding part longitudinal sectional view.

According to my invention, the winch proper is of any suitable construction, including for instance, in the conventional way, an electric motor 1 which drives, through a speed reducing mechanism or gear box 2, a drum 3 on which is coiled the hauling cable 4.

According to my invention, this winch proper is mounted on a rolling support constituting a railway carriage adapted to be moved along the rails 5 of the railway track, and this support is arranged in such manner that the effort exerted on cable 4 for a hauling operation produces a temporary locking of said support on the track, so that the winch can act in the same manner as a stationary winch, that is to say in the best possible conditions of fixation and stability.

Advantageously, the machine is devised in such manner that most of its weight is supported by one of the rails 5. The winding drum 3 may be

2

located either on the outside of the track, as in the embodiment of Fig. 1, or on the inside, as in the embodiment of Fig. 5.

In both cases, the weight of motor 1 is made approximately to balance that of drum 3 in such a manner that the center of gravity of the whole is located inside the track and in a vertical plane close to that of the rail 5 which is to support the major part of the weight, the rolling support then bearing on the other rail 5 through a mere carrier roller 6 which is relatively little loaded.

Anyway, the machine as a whole is reversible, i. e. the winch proper can be disposed at will on either of the rails 5.

The rolling support includes, in the embodiments shown by the drawing:

(a) A frame, constituted in the case of Fig. 1 by an assembly 7 and in that of Fig. 5 by a single cross bar 7', carrying at one end roller 6 and, at the other end, the winch proper;

(b) A winch base 8 provided with rolling elements, constituted for instance by two rollers 9; and

(c) Means for locking the machine on the track every time a traction is exerted through cable 4, for a hauling operation.

The locking means in question are preferably constituted by a device adapted to coact in a wedging manner with the rail that supports the major part of the weight of the machine, said locking means being therefore carried by base 8.

It will be readily understood that a wedge action locking device is particularly advantageous on the case of a hauling machine, since the intensity of the locking effect will then increase simultaneously with the hauling effort exerted by cable 4.

In the embodiment of Figs. 1 to 4, the hauling effort exerted through cable 4 causes the whole of the machine to pivot about a vertical axis so as to bring into contact with the rail 5 that supports the major part of the weight at least one friction part.

For this purpose, as shown by the drawing, base 8 is made of inverted U section so as to fit with a sufficient play about the weight supporting rail 5. The inner walls of the flanges of this base carry toothed jaws 10, pivotal about vertical axes 10a (see in particular Fig. 2). In the embodiment illustrated by the drawing, base 8 carries four jaws 10, two on either side of rail 5, their teeth being inclined in a given direction for two diagonally opposed jaws and in the opposite direction for the two other jaws. All these

jaws are adapted to remain at a distance from the corresponding rail 5 as long as the machine is positioned in straight relation to the track.

In order to keep the machine in this straight position with respect to the rail, for instance when it is to run along said track, base 8 is fitted with retractable guiding means for opposing pivoting thereof about a vertical axis. Said means may be constituted, as shown by the drawing, by two upwardly retractable stirrups 11 in the shape of inverted U respectively mounted at the front and rear ends of base 8 so as to be vertically slideable therein and the branches of which stirrups are at a distance from each other just a little greater than the width of the rail so as to ensure guiding without producing undue friction. Screws 8a carried by base 8 permit, by engagement in holes 11a of stirrups 11, of holding the stirrup in retracted position (solid lines).

This system works in the following manner:

When the machine is to be run along the track, stirrups 11 are left in the lower position. The rolling support is kept in normal straight position with respect to the track and jaws have practically no contact with rail 5 (position shown by Figs. 3 and 4). When it is desired to perform a hauling operation, the machine is stopped at the proper position on the track, stirrups 11 are retracted upwardly, and cable 4 is tied to the load to be hauled. The hauling effort, as soon as it takes place, causes the whole of the machine to pivot about a vertical axis, which brings two diagonally opposed jaws into contact with rail 5 and wedges them against the sides of said rail, with a force which rises proportionally with the traction force (position shown by Figs. 1 and 2).

In the embodiment illustrated by Figs. 5 to 9 inclusive, the application against the rails of friction elements, constituted for instance by toothed jaws 10 analogous to those above referred to, instead of being produced by a pivoting movement of the machine, is obtained as a consequence of a translatory displacement thereof (parallel to the track).

In this case, the lateral walls of base 8, at the ends thereof, converge toward rail 5, as shown by Fig. 8, so that any translatory longitudinal displacement of said base with respect to jaws 10 (the outer faces of which, adapted to cooperate with said portions of the lateral walls to base 8, are similarly inclined) wedges said jaws against the rail so as to ensure the desired locking effect.

Jaws 10 are provided with slots 14 in which are engaged transverse pins 13 carried by the lower ends of levers 12 pivoted to base 8 about horizontal axes parallel to said pins. Thus said jaws can be given the translatory displacements necessary for wedging them against the rail.

When the machine is to be run along the track levers 12 are in the positions shown as XY on Fig. 7, so that jaws 10 are in the positions shown on the right hand side of Fig. 8, out of contact with rail 5. In order to make use of the winch, the machine is stopped at the desired point of the track. The two levers 12 that are farther from the load to be hauled are then pivoted into the position shown. The corresponding jaws are then in the position shown by the left hand side of Fig. 7. From this time on, the hauling effort exerted by the winch tends, by reaction, to wedge said jaws against the rail with a force which is in proportion to the hauling force. Once the hauling operation has been performed, it will suffice to

restore levers 12 into positions XY, and the machine will be again free to move on the track.

It should be noted that, in a machine made according to the embodiment of Figs. 5 to 9, I may provide guiding and locking means on the side of the rolling support that is relatively but little loaded. For instance, as shown by Figs. 5 and 6, the end in question of cross member 7' is provided with a clasping device 15 adapted to engage the rail, so as to prevent tilting of the machine when the point where cable 4 is secured is relatively high.

Of course, the winch proper, together with its base could be mounted detachable from the remainder of the rolling support so as to permit, after they have been conveyed by said support to the desired point of the track, of removing them and suitably fixing them in suitable position with respect to the track.

20 The machine can advantageously be utilized on tracks running along a canal or a wharf.

25 In a general manner, while I have, in the above description, disclosed what I deem to be practical and efficient embodiments of the present invention, it should be well understood that I do not wish to be limited thereto as there might be changes made in the arrangement, disposition and form of the parts without departing from the principle of the present invention as comprehended within the scope of the accompanying claims.

What I claim is:

30 1. A hauling machine which comprises, in combination, a railway carriage, a motor winch mounted on said carriage so as to have its center of gravity nearer to one of the rails of the track on which said carriage is supported than to the other, with the winding drum of said winch on one side of said first mentioned rail, a part rigid with said winch extending in the direction of said first mentioned rail, and at least two toothed jaws pivoted to said part about vertical axes disposed one ahead of the other and on opposite sides of said first mentioned rail respectively, said part being pivotable with respect to said rail about a vertical axis to bring said jaws into frictional engagement with said rail.

35 2. A hauling machine which comprises, in combination, a railway carriage, a motor winch mounted on said carriage so as to have its center of gravity nearer to one of the rails of the track on which said carriage is supported than to the other, with the winding drum of said winch on one side of said first mentioned rail, a part rigid with said winch extending in the direction of said first mentioned rail, and at least four toothed jaws pivoted to said part about vertical axes disposed in two pairs one ahead of the other, the two jaws of each pair being located on opposite sides of said first mentioned rail respectively, said part being pivotable with respect to said rail about a vertical axis to bring two of said jaws into frictional engagement with said first mentioned rail.

40 3. A hauling machine which comprises, in combination, a railway carriage adapted to be brought into oblique position with respect to the track by which it is supported, a motor winch mounted in fixed position on said carriage so as to have its center of gravity nearer to one of the rails of said track than to the other, with the winding drum of said winch located on one side of said first mentioned rail, a part rigid with said carriage extending in the direction of

said first mentioned rail, and at least two toothed jaws pivoted to said part about vertical axes disposed one ahead of the other and on opposite sides of said first mentioned rail respectively, so as to come into frictional engagement with said rail when said carriage is oblique to said track.

4. A hauling machine which comprises, in combination, a railway carriage having two wheels for running on one of the rails of the track by which it is supported and only one wheel for running on the other rail, whereby said carriage can be brought into oblique position with respect to said track, a motor winch mounted in fixed position on said carriage so as to have its center of gravity nearer to the first mentioned rail than to the other, with the winding drum of said winch located on one side of said first mentioned rail, a part rigid with said carriage extending in the direction of said first mentioned rail, and at least two toothed jaws pivoted to said part about vertical axes disposed one ahead of the other and on opposite sides of said first mentioned rail respectively, so as to come into frictional engagement with said rail when said carriage is oblique to said track.

5. A hauling machine which comprises, in combination, a railway carriage adapted to be brought into oblique position with respect to the track by which it is supported, a motor winch mounted in fixed position on said carriage so as to have its center of gravity nearer to one of the rails of said track than to the other, with the winding drum of said winch located on one side of said first mentioned rail, a part rigid with said carriage extending in the direction of said first mentioned rail, and at least four toothed jaws pivoted to said part about vertical axes disposed in two pairs one ahead of the other, the two jaws of each pair being located on opposite sides of said first mentioned rail respectively, so that two of them come into frictional engagement with said rail when said carriage is oblique to said track.

6. A hauling machine which comprises, in

combination, a railway carriage having two wheels for running on one of the rails of the track by which it is supported and only one wheel for running on the other rail, whereby 5 said carriage can be brought into oblique position with respect to said track, a motor winch mounted in fixed position on said carriage so as to have its center of gravity nearer to the first mentioned rail than to the other, with the 10 winding drum of said winch located on one side of said first mentioned rail, a part rigid with said carriage extending in the direction of said first mentioned rail, and at least four toothed jaws pivoted to said part about vertical axes disposed in two pairs one ahead of the other, the two jaws of each pair being located on opposite sides of said first mentioned rail respectively 15 so that two of them come into frictional engagement with said rail when said carriage is oblique to said track.

7. A hauling machine for use on a railway track which comprises, in combination, a support adapted to rest on a rail of said track, a winch mounted in fixed position on said support with its winding drum on one side of said rail, and at least two jaws carried by said support on either side of said rail frictionally to engage opposite sides of said rail said jaws being located each at a distance from the axis of said drum, whereby said support is fixed by said jaws with respect to said rail in response to the oblique pulling action of said winch.

BLONDELLE, ABEL LÉO CHARLES.
